ATTORNEY.

UNITED STATES PATENT OFFICE

LORENE McBEE, OF ST. LOUIS, MISSOURI

DOLL AND TOY ANIMAL

Application filed October 4, 1929. Serial No. 397,246.

This invention relates to dolls and toy animals of the type that consist of a fabric casing filled with cotton or some other material of a similar nature.

5 The main object of my invention is to provide an inexpensive doll or toy animal that has all of the desirable features and characteristics of the conventional rag doll or stuffed animal, and the added advantage of presenting a natural or life-like appearance.

Another object is to provide a stuffed fabric doll or toy animal that is inexpensive to manufacture and easy to produce, and of such design or construction that the face portion 15 of same can be changed or modified easily, during the process of manufacture, to produce different expressions or to produce irregularities such as are found in the faces of human beings and animals.

20 Figure 1 of the drawings is a front elevational view of the casing of the face portion of a doll head constructed in accordance with my invention.

Figure 2 is a rear elevational view of said 25 casing.

Figure 3 is a vertical sectional view, taken on the line 3—3 of Figure 1.

Figure 4 is a front elevational view of said 30 casing, after it has been stuffed or filled.

Figure 5 is a vertical sectional view, taken on the line 5—5 of Figure 4.

Figure 6 is an elevational view, showing the back piece of the head portion attached to the casing of the face portion.

35 Figure 7 is a vertical sectional view, taken on the line 7—7 of Figure 6.

Figure 8 is an elevational view, showing the head casing reversed or turned inside out and in readiness to receive the cotton or 40 similar material that is used as a filling for the head casing.

Figure 9 is a vertical sectional view, taken on the line 9—9 of Figure 8.

Figure 10 is a vertical sectional view, similar to Figure 9, showing the head casing stuffed or filled; and

Figure 11 is a perspective view of a finished or completed doll head embodying my invention.

50 In the accompanying drawings which illus-

trate the preferred form of my invention, A and B in Figures 9 and 10 designate two pieces of shaped fabric, preferably non-stretchable fabric, whose edge portions are joined together in any suitable way, preferably by thread stitches, so as to form a casing that is adapted to be stuffed or filled with a soft, fluffy substance, such as cotton, kapok or other suitable material α of a similar nature, so as to form the head portion of a doll or toy 60 animal. The face portion of the article is also composed of a fabric casing, stuffed or filled with a material like cotton or kapok, but the casing of the face portion is provided with a front piece C formed of stretchable fabric, or fabric that has some elasticity. Preferably, the casing of the face portion is formed from a piece of cloth of the kind known commercially as jersey, which is sewed or connected in any other suitable way at its 65 peripheral edge to the front piece A of the casing of the head portion.

In order to produce a face having features that closely simulate the features of a human face, the front piece C of the face portion is 70 permanently connected to the front piece A of the head casing in the zone of the eyes, the nose and the mouth, and cotton, kapok or other suitable material γ is introduced into or packed into the casing of the face 75 portion, so as to form a face provided with a protruding nose, chin, cheeks and forehead that are of irregular contour or shape and which closely simulate the features of a human face, the front piece C of the face 80 casing having sufficient elasticity or being capable of stretching sufficiently, to insure its being stretched taut, and held in snug engagement with the bulged portions of the filling γ of the face portion that constitute 85 the nose, chin, cheeks, and forehead of the face. In the form of my invention herein shown, the stretchable front piece C of the face casing is attached to the front piece A of the head casing by a straight row or 90 slightly curved row of stitches 1 that constitute the mouth line located between the lips 2 of the face, and also by two substantially circular- or ring-shaped rows of stitches 3 that define or form the outlines of the eyes 100

4 of the face. At the point where the nose 5 of the face is located, the front piece C of the casing is attached to the front piece A of the head casing, either by a straight row of 10 stitches 6, or by two separated stitches that constitute or represent the nostrils of the nose. At a point below the mouth the front piece C of the face casing is attached to the front piece A of the head casing by a 15 segmental row of stitches 7 that outlines the chin or lower portion of the face and separates it from the neck portion of the doll. It is immaterial, however, so far as my broad idea is concerned, what means is employed to permanently connect the front piece C of the 20 face portion to the front piece A of the head casing in the zone of the eyes, the nose and the mouth. The eyes 4 and lips 2 of the face can be produced in various ways without departing from the spirit of my invention, such, 25 for example, as applying paint or coloring material to the fabric C that constitutes the front piece of the face casing or attaching objects to said piece of fabric C so as to represent eyes and lips. Usually, the face piece C will be formed from a flesh colored piece of stretchable fabric that is colored or tinted in such a way as to produce rosy cheeks and to simulate hair 8 that surrounds the face of the doll.

30 It is also immaterial, so far as my broad idea is concerned, what procedure is employed to fill or stuff the head casing and the face casing and combine the three pieces 35 of material A, B and C that constitute said casings. I prefer, however, to construct the head of the article in the following manner, as I have found that such a method of manufacture enables a doll head or toy animal head that is very realistic or life-like, to be 40 produced easily, quickly and at a low cost. The first step in the method of manufacturing the head is to attach a piece of stretchable material C, such as jersey, to a piece of fabric 45 A, preferably non-stretchable fabric, such as sateen or cotton cloth, so as to form the casing of the face portion of the article, said pieces of material being cut to the shape shown in Figures 1 and 2 and joined together 50 at their peripheral edges by a circular row of stitches 7 that extends around the major portion of the peripheral edges of said pieces, but which terminates at opposite sides of a gap, designated by the reference character 7^a 55 in Figure 2, that constitutes a slit or opening through which the filling y can subsequently be packed into the casing of the face portion. This circular row of stitches 7 outlines the chin portion of the face, as 60 previously described, and separates the same from the neck portion of the doll. The fabric A that constitutes the front piece of the head casing is preferably used to form part of the body casing, and the upper end portion 65 of same comprises a substantially circular-

shaped part attached to a neck portion that is of substantially less width than the diameter of the head casing. The front piece C of the face casing is of substantially the same outline and dimensions as the upper end portion of the fabric A, but terminates at a point slightly below the neck portion and is attached to the piece of fabric A by a horizontal row of stitches 9. In the completed doll the lower end portion of the face piece C, located below the chin of the face, constitutes the outer covering of the neck portion of the doll. While the pieces A and C are arranged in a flat condition and in superimposed relation, the stitches 1, 3 and 6, previously referred to, that constitute the mouth slit, the outline of the eyes and the nostrils are inserted, thereby enabling the face casing to be produced quickly and easily by a simple sewing operation.

85 The next step in the operation of producing the face is to fill the casing formed by the pieces of fabric A and C, which operation is performed by introducing cotton, kapok or other similar material y through the gap 7^a at the upper end of the casing, and packing said material y in the casing in such a way as to produce a protruding forehead, a protruding nose, convexed cheeks that bulge outwardly and which merge into a chin that protrudes beyond the mouth slit, and an upper lip portion that bulges forwardly between the stitches 1 and 6 that connect the face piece C to the other member A of the face casing.

90 After the face casing has been filled and molded, as above described, and as illustrated in Figures 1 to 5, inclusive, the filled or stuffed face casing is arranged in superimposed relation with a piece of fabric B that constitutes the back piece of the head casing in such a way that the stretchable fabric C which constitutes the front piece of the face casing is interposed between the two pieces of nonstretchable fabric A and B that constitute the head casing, as shown in Figure 7, 100 the said three pieces of material B, C and A being thereafter joined together by a circular row of stitches 10, which, as shown in Figure 6, extends around the peripheral edges of said pieces, but not transversely across the contracted intermediate portions of said pieces that constitute the neck portion of the doll. In the above described operation of attaching the stuffed face casing to the back piece B of the head casing the gap or 105 filling opening 7^a of the face casing becomes closed by the stitches 10, thereby finishing the operation of producing the face portion of the article. The next step is to turn the structure inside out, the same as a sock or stocking is turned, so as to cause the face piece C to be arranged on the outside of the structure, as shown in Figure 8 and 9. The 110 final step in the operation of constructing the head is to fill the head casing, formed by 115

the pieces A and B, with cotton, kapok or similar material α , which operation is formed simultaneously with the operation of stuffing or filling the body casing composed of the pieces of fabric A and B whose upper end portions constitute the head casing and part of the face casing.

The face of the doll can be decorated or painted at the completion of the stuffing operation, or, if desired, the stretchable piece of fabric C that constitutes the face of the doll can be stamped, painted or otherwise marked to produce or simulate eyes, lips and highly colored checks, prior to the operation of attaching the face piece C to the front piece A of the head casing. An article of the construction above described has all of the desirable features or characteristics of a rag doll or stuffed toy animal, and it has the added advantage of presenting a very realistic and life-like appearance, due to the fact that the face has a protruding nose, forehead, chin and cheeks, that are of irregular shape or contour and which can be modified easily during the course of manufacture to produce different expressions, or to produce irregularities of feature, such as exist in human faces. The advantages above described, coupled with the fact that the article can be produced easily, quickly and at a very slight increase in the cost of manufacturing a rag doll or stuffed toy animal of conventional design, provided with a flat face or face devoid of any expression or protruding features, makes my invention of great commercial utility and enables children to be supplied with a very attractive and practical toy that can be used safely by a small child without liability of causing injuries of the kind that are produced from dolls or toy animals formed from rigid or hard molded material, or from objects that can be easily torn apart or disassociated.

Having thus described my invention, what I claim as new and desire to secure by Letters Patent is:

1. An article of the kind described, provided with a face portion formed from a front piece of stretchable fabric and an opposed piece of non-stretchable fabric secured together at their peripheral edges, means for permanently connecting said two pieces together in the zone of the eyes, nose, mouth and chin, and a soft, fluffy filling material packed in the space between said pieces of fabric so as to produce protruding face features.

2. An article of the kind described, provided with a head formed from three pieces of fabric cut to form the outline of a head and joined together at their peripheral edges so as to form a head casing and a face casing, the front piece of the face casing being permanently connected to the intermediate piece of fabric in the zone of the eyes, the nose and the mouth, and a soft filling material packed

into said casings in such a way as to produce a head having a face provided with protruding features that vary in shape and outline according to the way said packing is rammed into said face casing.

3. An article of the kind described, provided with a head casing whose opposed members are formed from pieces of fabric which also constitute the body casing of the article, a piece of stretchable fabric attached at its peripheral edge to the head casing and joined to the front piece of the head casing by stitches disposed so as to form the outline of the eyes, the chin, the mouth line and the nostrils, and a soft fibrous material packed into the space between said stretchable face piece and the front piece of the head casing in such a way as to produce protruding face features of irregular shape or contour.
